Primary Examiner — Marianne Pandozzi*(74) Attorney, Agent, or Firm* — McKee, Voorhees & Sease, PLC(57) **CLAIM**

I claim the ornamental design for a baseball cup, substantially as shown.

DESCRIPTION

FIG. 1 is a perspective view of a baseball cup showing my new design with the cap in closed position;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a perspective view of the baseball cup showing my new design with the cap in open position;

FIG. 9 is a front elevational view thereof;

FIG. 10 is a rear elevational view thereof;

FIG. 11 is a left side elevational view thereof;

FIG. 12 is a right side elevational view thereof; and,

FIG. 13 is a top plan view thereof.
